JAMES CASSIDY, OF CHICAGO, ILLINOIS.

REMOVABLE HANDLE FOR ROCK-SHAFTS.

1,160,259.

Specification of Letters Patent. Patented Nov. 16, 1915.

Application filed July 27, 1914. Serial No. 853,395.

To all whom it may concern:

Be it known that I, JAMES CASSIDY, a citizen of the United States, and a resident of Chicago, in the county of Cook and State 5 of Illinois, have invented certain new and useful Improvements in Removable Handles for Rock-Shafts, of which the following is a specification.

This invention relates to a removable 10 handle which is primarily to be used on the rock shaft of a sanding device for street and other railways.

The objects of the invention are to obtain a removable handle by means of which 15 one or more rock shafts may be actuated, to operate a sanding device, to discharge sand before one or more of the trucks of an electric or other car, or to the rear of said trucks.

20 A further object is to obtain a removable handle by means of which a sanding device may be operated for all the above enumerated conditions.

A further object is to obtain a device of 25 the kind named which can be operated readily and quickly, for any and all the above purposes, which is not liable to get out of order, to be broken, or to fail in operation.

30 A further object is to obtain a device which is economical in construction, and readily understood by motor men and other persons required to use the same.

To those familiar with the operation of 35 electric motor cars it is known that at times it is very desirable to discharge sand in front of the forward pair of wheels of the car; that at other times, in making what is known as an emergency stop, it is desirable 40 to discharge sand in front of more than one pair of said wheels, and in other cases, as where a car is standing still on a grade, or where it is desired to back a car, it is desirable to discharge sand in the rear of one 45 or more of said pair of wheels.

I have illustrated a handle embodying this invention, and so much of a sanding device as is required to understand the application 50 of the device thereto, in the drawings accompanying and forming a part of this specification; in which drawings Figure 1 is a top plan view of the device, and of the rock shafts of a sanding device. Fig. 2 is a vertical section of the device and of said shafts. 55 Fig. 3 is a horizontal section, on line 3—3 of Fig. 2, viewed in the direction indicated

by the arrows. Fig. 4 is a horizontal section, on line 4—4 of Fig. 2, viewed in the direction indicated by the arrows. Fig. 5 is an elevation of the handle, with a part 60 thereof in section. Fig. 6 is a vertical section, on line 6—6 of Fig. 5, viewed in the direction indicated by the arrows. Fig. 7 is a top view of the standard of the device. Fig. 8 is a side elevation of the upper end 65 of said standard. Fig. 9 is a perspective of a latch forming an element of the device. Fig. 10 is a perspective of a bolt body and bolt thereon and of a latch engageable therewith. And Fig. 11 is a plan view of the 70 upper end of a tube shaft which may be operated by the device.

A reference character applied to designate a given part indicates said part throughout the several figures of the drawing wherever 75 the same appears.

A is a vertical shaft, to which the device embodying this invention is removably attachable.

B and C, are, respectively, tube shafts 80 mounted on, and concentric with, shaft A. Shaft A may be turned independently of tube shafts B, or C; or it may be turned with one or both of said tube shafts, as desired, by means of the device embodying 85 this invention.

D is a pulley on the lower end of shaft C, and d, d, are cables on said pulley.

D¹ is a pulley on the lower end of tube shaft B; d¹, is a cable on said pulley D¹; 90 D² is a pulley on tube shaft A and d², is a cable on said pulley. The several pulleys D, D¹, and D², actuate, by means of cables d, d¹ and d², the valves of corresponding sand boxes, but as said sand boxes and valves 95 form no part of this invention the same are not illustrated.

E is a handle, which is provided with hub F, and said hub is provided with a rectangular hole (f), therethrough. The upper 100 end of shaft A is rectangular, and fits loosely in hole f, (shown by broken lines in Fig. 5).

G is a wedge in hole f of hub F, H is a screw threaded bolt which is attached to wedge G and h is a butterfly nut on bolt H.

h¹ is a spring to yieldingly hold bolt H advanced. By turning the butterfly nut h down on bolt H, spring h¹ is retracted and wedge G is raised in hub F, and thereby 110 said hub is rigidly secured on said shaft A. To remove the handle from said shaft the

butterfly nut h is turned upon bolt H and said bolt is forced down, to loosen wedge G . When handle E is in place, as above described, on shaft A , the turning of said handle turns, or rocks said shaft A .

5 I, J, are longitudinally movable bolts or latches, which are yieldingly held in an advanced position by the springs K, L. The rear ends of said bolts are beveled, as at i , 10 j , and M, N are shoulders adjacent to said ends, which are engageable with spring latches O, P, respectively, and when said latches are in engagement with said bolts the bolts are retained in a retracted position, against the resiliency of springs K, L.

15 Q is a push button to spring latch O, and R is a push button to spring latch P.

S is a button, or abutment on bolt I, by means of which it may be retracted by the 20 operator, and T is a like button or handle to bolt J. Buttons S and T, respectively move laterally in slots t , t , when said bolts I, J, move longitudinally.

U is a hole in the upper end of tube B, and 25 bolt I is engageable in said hole and when said bolt is in an advanced position, (in said hole) the movement of the handle E turns said tube.

30 U¹ is a like hole in tube C, and bolt J engages with said hole in the same manner, and for the same purpose that bolt I engages with the hole U.

35 V is a bolt secured in body V¹, and said body is pivotally mounted on screw or pivot V².

V³ is a tie rod, and V⁴ is a bell crank and handle. Tie rod V³ connects pivoted body V¹ and bell crank V⁴.

40 V⁵ is the pivot on which bell crank V⁴ turns, and V⁶ is a spring which yieldingly holds said bell crank and body V¹ in position with the bolt V advanced.

45 W is a hole in standard X, with which the bolt V is engageable when the handle E is moved into position to turn shaft A so that the valves of a sand box, (or other device) are open, or operative. The purpose of said bolt V is merely to hold the handle E in operated position and relieve the operator.

50 When the handle E is to be again put into an inoperative position the handle V⁴ is moved toward handle E, (Fig. 1) and bolt V thereby retracted, or disengaged from hole W.

55 With the bolts I, J, held in a retracted position by latches O, P, to operate the device the handle E is turned, turning therewith the shaft A. When shaft A and tube shaft B are both to be turned, the push button Q is depressed, before said handle is turned. To turn tube shaft C the button R is forced in, to disengage latch P, before handle E is turned. To turn shaft A and both tube shafts, (B and C), push buttons 60 Q, R are both forced in to disengage both

latches O and P, and handle E is then turned. When handle E is turned the bolt V automatically engages with the hole W, to maintain said handle in its turned position until it is desired to return said handle to its initial place, when the bell crank V⁴ is forced toward handle E, thereby withdrawing bolt V from hole W.

70 I claim:

1. A handle having a socket with an inclined face thereto and a table at the upper end of said socket, a wedge within said socket, said wedge having an inclined face adapted to co-act with said inclined face of said socket, said socket adapted to fit over the squared end of a shaft, a screw threaded shaft pivotally and non-rotatably attached to said wedge and arranged to extend through said table, a spring arranged to abut against said table and said wedge to yieldingly hold said wedge in an inoperative position, and a screw threaded nut rotatably mounted on said bolt and adapted when turned to move said wedge longitudinally against the resiliency of said spring. 75

2. The combination of a handle having a hub, a standard, a rock shaft mounted in said standard, the upper end of said shaft rectangular in shape and said hub provided with a rectangular aperture therethrough 80 adapted to fit loosely on said upper end of the rock shaft, a wedge longitudinally movable in the aperture in said hub, means to move said wedge to secure said hub on said shaft, a plurality of tube shafts loosely 85 mounted on said rock shaft, mechanisms on said handle and tube shafts respectively adapted to bind said tube shafts to said handle, said mechanisms comprising, respectively, bolts yieldingly held in an advanced 90 and operative position, means whereby said bolts may be separately retracted to an inoperative position, means to hold said bolts in a normally retracted position, and means to separately release said bolts from said 95 holding means to render said bolts operative to bind a selected tube shaft to said handle. 100

3. The combination of a standard, a rock shaft mounted in said standard, a handle on said shaft, a plurality of tube shafts loosely 105 mounted on said rock shaft, interlocking mechanisms respectively adapted to bind said tube shafts to said handle, said interlocking mechanisms respectively comprising bolts yieldingly held in an advanced and operative position, means whereby said bolts may separately be retracted, and means to hold said bolts normally in said retracted position, means to separately release said holding mechanisms, thereby permitting said bolts to be operative, and bind said rock shafts and handle together, and means on said standard and handle adapted to engage and hold said handle in a determined 110 position. 120

125

130

4. The combination of a handle having a hub, a standard, a rock shaft mounted in said standard, means to secure said hub to said rock shaft, a plurality of tube shafts 5 loosely mounted on said rock shaft, mechanisms on said handle and tube shafts respectively adapted to bind said handle and tube shafts together, said mechanisms respectively comprising bolts yieldingly held 10 in an advanced and operative position, means whereby said bolts may be separately retracted to an inoperative position, means to normally hold said bolts in a retracted position, and means to separately release said bolts from said holding means and thereby render said bolts operative to bind 15 a selected tube shaft to said handle.

JAMES CASSIDY.

In the presence of—

CHARLES TURNER BROWN,
CHARLES B. HEBRON.
